(57) CLAIM

The ornamental design for a jacket as shown and described.

DESCRIPTION

FIG. 1 is a rear, left side perspective view of a jacket showing my new design;

FIG. 2 is a rear view thereof;

FIG. 3 is a rear, right side perspective view thereof;

FIG. 4 is a right side view thereof; and,

FIG. 5 is a left side view thereof.

The area of the sleeves immediately adjacent to the solid lines depict portions of the jacket that form no part of the claimed design. The broken lines depicting the remainder of the jacket form no part of the claimed design.

1 Claim, 5 Drawing Sheets(56)
